[57] CLAIM

The ornamental design for a poultry decking module, as shown and described.

DESCRIPTION

FIG. 1 is a top plan view of a poultry decking module showing my new design;

FIG. 2 is a bottom plan view thereof;

FIG. 3 is a side elevational view thereof;

FIG. 4 is a side elevational view opposite of the side shown in FIG. 3 thereof;

FIG. 5 is an end elevational view thereof;

FIG. 6 is an end elevational view opposite of the end shown in FIG. 5 thereof;

FIG. 7 is a top plan view of a poultry decking module showing a second embodiment of my new design;

FIG. 8 is a bottom plan view of FIG. 7 thereof;

FIG. 9 is a side elevational view of FIG. 7 thereof;

FIG. 10 is a side elevational view opposite of the side shown in FIG. 9 thereof;

FIG. 11 is an end elevational view of FIG. 7 thereof;

FIG. 12 is an end elevational view opposite of the end shown in FIG. 11 thereof;

FIG. 13 is a top plan view of a poultry decking module showing a third embodiment of my new design;

FIG. 14 is a bottom plan view of FIG. 13 thereof;

FIG. 15 is a side elevational view FIG. 13 thereof;

FIG. 16 is a side elevational view opposite of the side shown in FIG. 15 thereof;

FIG. 17 is an end elevational view of FIG. 13 thereof;

FIG. 18 is an end elevational view opposite of the end shown in FIG. 17 thereof;

FIG. 19 is a top plan view of a poultry decking module showing a fourth embodiment of my new design;

FIG. 20 is a bottom plan view of FIG. 19 thereof;

FIG. 21 is a side elevational view of FIG. 19 thereof;

FIG. 22 is a side elevational view opposite of the side shown in FIG. 21 thereof;

FIG. 23 is an end elevational view of FIG. 19 thereof;

FIG. 24 is an end elevational view opposite of the end shown in FIG. 23 thereof.
